INCINERATOR

Charles C. Reynolds, Dallas, Tex.

Application June 23, 1952, Serial No. 295,014

2 Claims. (Cl. 110—18)

1

This invention relates to incinerators and more particularly to a novel wall construction for incinerators particularly designed for burning cotton burrs which accumulate around cotton gins.

The principal object of the invention is to provide a multiple wall construction for incinerator towers, consisting of superposed courses of specially designed concrete blocks having voids which are in communication from the lowest to the highest course to provide vertical passages for the escape of hot gases generated by the heat of the incinerator.

Another object of the invention is to provide an incinerator wall construction composed of two or more horizontal courses of tile or concrete blocks having vertical passages, the passages of the courses being in communication vertically to provide longitudinal passages from the bottom to the top of the incinerator, with provision for effecting lateral communication between the longitudinal passages at a point adjacent to the bottom of the incinerator, thus to release hot gases from the walls and prevent generation of heat therein to preclude too rapid deterioration.

Still another object of the invention is to provide the innermost wall or liner of the incinerator tower, which is usually terminated at a point above the mid-section of the tower, with an annular cap to close the upper ends of the longitudinal passages but permitting escape of hot gases therefrom through circumferentially spaced escape vents formed by lateral passages effecting communication with the longitudinal passages and the inside of the incinerator. Such an arrangement insures cooling of the inner wall or liner as well as the hot gases rising there through away from the inner surface of the next adjacent wall.

Yet another object of the invention is to provide an incinerator composed of superposed concrete blocks or tile in which the lowermost course has open head joints for the escape of moisture of condensation and further providing for expansion and contraction through the elimination of head joints in the inner wall and providing bed joints in every fifth course in the inner wall, although providing bed joints between each course in the outer walls. Since there is no direct communication between the combustion area of the burner and any of the wall passages, there remains only the induced heat to be disposed of through the passages, hence, the walls are maintained at a lower temperature than if the passages were required to carry off direct heat of combustion. Thus, re-

2

placements are prolonged for indefinite periods.

With the foregoing objects in view, the invention has further reference to certain features of accomplishment which will become apparent as the description proceeds, taken in connection with the accompanying drawings wherein:

Figure 1 is a side elevational view of an incinerator tower constructed according to the present invention with parts broken away to show the wall construction.

Figure 2 is a fragmentary sectional view of the wall construction on a larger scale.

Figure 3 is a fragmentary view in transverse section taken on line 3—3 of Figure 1, and

Figure 4 is the transverse sectional view taken on line 4—4 of Figure 1.

Continuing with a more detailed description of the drawing, reference numeral 10 denotes a circular concrete base on which is superimposed the initial course of concrete blocks or tile 11 of the outer wall A and which are in juxtaposition to the blocks 12 constituting the lowest course of the inner wall or liner B. The outer course of blocks has bed joints but is devoid of open head joints in order to provide for the escape of moisture of condensation as well as to provide for expansion and contraction.

The blocks of the courses of both inner and outer walls are offset inwardly from the bottom to the top of the tower to produce the frusto coniform construction shown. The blocks 13 forming the course next above the course 11 of the outer wall are each provided with parallel vertical voids 14 as well as transverse passages 15 which effect communication between the voids 14 and atmosphere. Also, the blocks 11 are provided with passages 16 which directly or indirectly communicate with like passages 17 in the walls of blocks 12 forming the course next to the bottom in the inner wall or liner B. The passages 17 are in communication with vertical voids 18 in the blocks 12.

The blocks 19 of the outer wall A as well as the blocks 20 of the inner wall B in the successive courses above the courses 11 and 12 are constructed identical to the blocks of the latter courses except that they do not possess the lateral or transverse passages of the blocks 11 and 12. However, the voids of the blocks of both the outer and inner walls are in communication to the top of each wall A and B. However, the inner wall or liner B terminates above the mid-section of the tower and the passages 21 of the blocks of the outer wall A are open at the top 55 of the tower which is embraced by a screen of

wire mesh 22 to intercept burning embers as a safety precaution. The passages 23 in the blocks of the inner wall or liner B are closed at their tops by an annular cap 24 but hot gases rising through the passages 23 of the inner wall find escape through lateral vents 25 which open into the incinerator. In this manner, the hot gases are diverted away from the inner surface of the outer wall A to prevent deterioration by exposure to excessive heat.

Between each course of the blocks in the outer wall A there are provided bed joints as well as head joints but in the inner wall B there are no head joints in the inner wall and bed joints are provided in every fifth course. This arrangement insures maximum expansion and contraction due to changes in temperature and prevents cracking of the blocks or masonry, thus prolonging the life of the incinerator.

Cotton burrs or other materials to be destroyed are blown through the inlet pipe 26 which is set into the walls of the incinerator at a suitable point spaced below the top of the inner wall B at a tangent. The position of the inlet pipe producing a swirling action and promotes combustion of the material as it enters the incinerator. The heat of combustion generates a draft upwardly through the passages of both the inner and outer walls and this draft influences cool air from atmosphere into the passages 21 and 23 through the openings 15 and 17, thus reducing the temperature of the walls. At no point is the heat of combustion permitted to enter the passages through the blocks except by induction and this heat, for the most part, is carried off at the tops of the outer and inner walls through their passages.

It is understood that while the drawing shows a single outer wall and a single inner wall or liner, the walls may be made up in the thickness of two or more blocks having vertical passages or voids, certain of which voids communicate with voids of adjacent blocks and with atmosphere to create a draft generated by the heat of combustion in the incinerator to prevent the storing of heat within the walls.

Manifestly, the construction (and process) as shown and described is capable of some modification and such modification as may be construed to fall within the scope and meaning of the appended claims is also considered to be within the spirit and intent of the invention.

What is claimed is:

1. In an incinerator, a combustion chamber comprising at least two walls including separate inner and outer series of superimposed blocks,

each block having vertical openings extending therethrough and communicating with the openings of the blocks of adjacent underlying and overlying courses of each series to define continuous upright passages spaced peripherally about the combustion chamber in each series; the passages in the outer series extending throughout the height of the incinerator and communicating with the atmosphere at the top and bottom of the incinerator; the passages in the inner series

extending from the bottom of the incinerator to a point above the mid-height of the incinerator but terminating substantially below the top of the incinerator, and said passages in the inner series communicating with the passages of the outer series at the bottom of the incinerator and opening into the interior of the combustion chamber adjacent the top only of the passages of the inner series, and cap means closing the passages of the inner series at the tops thereof.

2. In an incinerator, a combustion chamber comprising at least two walls including separate inner and outer series of superimposed blocks, each block having vertical openings extending therethrough and communicating with the openings of the blocks of adjacent underlying and overlying courses of each series to define continuous upright passages spaced peripherally about the combustion chamber, the passages in the outer series extending throughout the height of the incinerator and communicating with the atmosphere at the top and bottom of the incinerator, and the passages of the inner series extending from the bottom of the incinerator to a point above the mid-height of the incinerator but terminating substantially below the top of the incinerator, and said inner series passages communicating with the passages of the outer series at the bottom of the incinerator and opening into the interior of the combustion chamber adjacent the top only of the inner series.

CHARLES C. REYNOLDS.
